WRIST WATCH STRAP

Theodore L. Ashworth, 2128 N. Lynhurst, Apt. B,
Indianapolis, Ind. 46224

Filed Aug. 28, 1974, Ser. No. 501,230

Term of patent 14 years

Int. Cl. D11—01

U.S. Cl. D45—4 E

Fig. 1

Fig. 2

Fig. 3

Fig. 4

FIG. 1 is a top plan view of a wrist watch strap showing my new design;

FIG. 2 is a side elevational view thereof;

FIG. 3 is a bottom plan view thereof; and

FIG. 4 is a vertical sectional view taken on the line 4—4 of FIG. 1.

I claim:

The ornamental design for a wrist watch strap, as shown and described.
